UNITED STATES PATENT OFFICE

2,453,082

HOISTING APPARATUS

Pierre Jean-Marie Théodore Allard, Chantilly, France, assignor to Societe Francaise de Construction de Bennes Automatiques, Persan (Seine-et-Oise), France

Application May 15, 1945, Serial No. 593,827
In France February 4, 1944

2 Claims. (Cl. 212—93)

1

The present invention relates to hoisting apparatus comprising a horizontal or somewhat inclined runway on which travels a trolley to which is suspended a grab bucket or loading and unloading engine and which is displaced in one direction under the action of the hoisting rope and in the contrary direction under the action of a counterweight, forming a recall device, which becomes preponderant as soon as the bucket is suspended to its head or crown and the rope ceases to exert a traction on the trolley, the recall device being so disposed as to stop the trolley either at a fixed filling point or at any desired point during its return to the filling point, with a view to changing the filling point as may be necessary.

In apparatus of this type, the filling point is determined by an abutment—stationary in the case of a fixed filling point, and adjustable in the contrary case—against which the trolley or its counterweight, urged by the traction of the hoisting rope, comes to stop. When the trolley is thus stopped, the hoisting rope is unwound from its winch, the bucket becomes released from its head or crown and free to move down into contact with the goods to be hoisted (its weight overcoming the recall action of the counterweight, thereby maintaining the trolley in its stopped position). At the same time, a brake operated by the bucket head or crown, when the latter is liberated from the bucket weight, maintains the trolley in its stopped position. Upon winding up the hoisting rope around its winch, the bucket becomes filled, rises up and is gripped in its head, the brake is released and the counterweight urges the trolley towards the dumping point.

The invention consists in associating the abutment with a spring or springs intended to be compressed by the thrust exerted by the trolley or its counterweight and to relax as soon as the hoisting rope is slackened, in order to facilitate or accelerate setting in motion of the trolley, to reduce the mass of the counterweight and avoid untimely opening of the bucket at the moment of its being gripped in the bucket head.

Compression of the spring and, therefore, the recalling strength thereof, is a function of the weight of the load raised. This spring may be disposed in series with stronger effort limiting springs, intended to collapse in the event of abnormal efforts. Such effort limiting springs may be associated with a general switch for interrupting, in the event of abnormal efforts, the current feeding the hoisting motor.

Further features of the invention will be ap-

2

parent from the following description, with reference to the accompanying drawings, which show, by way of example, different embodiments of the invention, and in which:

Fig. 1 is a diagrammatical view showing a hoisting apparatus with variable filling point, to which the invention is applied;

Fig. 2 shows resilient abutment means, the counterweight being at the highest point of its stroke, corresponding to the filling point and the abutment being so adjusted as to cause the trolley to effect the longest possible run;

Fig. 2a is a horizontal cross-sectional view along the line 2a—2a of Fig. 2;

Fig. 3 shows another adjustment of the yieldable abutment, corresponding to another filling point and a reduced run of the trolley;

Figs. 4 and 5 are, respectively, an end view and a side view of a modified form of the invention;

Fig. 6 shows a modification in which the yieldable abutment cooperates with the trolley.

Referring to the drawings, 1 denotes a trolley which is adapted to travel on a runway 2 and is held under tension in the direction of arrow F¹, i. e., towards the filling points, by a hoisting rope or cable 3, and in the direction of arrow F², i. e., towards the dumping points, by a rope or cable 5 passing around a sheave 6 and to which is suspended a counterweight 7.

Trolley 1 supports a usual gripping head or crown 8 for bucket 4. In the example chosen, this head is suspended from a lever 9, pivoted at 10 to the trolley, and having a brake 11, which may be applied to the runway 2 by means of a spring 12.

Referring to Fig. 2, the counterweight 7 is guided between two bars 13, 14 and its upstroke may be limited by abutments 15, 15a. In the example chosen these abutments are integral with a rod 16, so mounted that its lower end portion is rotatable in a tie 17 and ends in a head 30. Between the latter and the tie 17 are interposed two springs 31, 32, separated by a washer 33.

Tension of spring 31 is such that said spring is completely compressed when the bucket is filled up and suspended from the hoisting rope. It must, however, be very important, in order to cause the trolley to be rapidly set in motion, as explained hereinafter.

The tension of spring 32 is such that said spring is compressed when, for any reason (such as the bucket being entangled in the upward course of its travel, excessive load, jamming of the bucket in a tank or silo, etc.) the hoisting apparatus is liable to be subjected to abnormal

efforts. Tension of said spring is, therefore, such that it will be compressed when the normal hoisting effort tends to be exceeded, whereupon the two springs 31, 32 being compressed, the washer 33 engages a switch 34, which cuts off the electric current in the whole plant.

As shown in Figs. 2 and 3, the abutments 15, 15a are identical but disposed in two vertical perpendicular planes, and the counterweight 7 has a slot 18 of elongated form, corresponding to that of the abutments. The rod 16 may be so turned that one or the other of these abutments 15, 15a is perpendicular to slot 18, the counterweight being stopped by said abutment.

Fig. 4 shows another embodiment of the invention, in which there is but one abutment 19, the height of which may be instantaneously adjusted, either through the medium of hand-operated control means or by a continuously rotating electric motor, so as to vary the filling point at each operation, such continuous rotation being automatically reversible by means of reversing switches at both ends of the trolley's run.

In the embodiment shown, abutment 19 is secured to the upper end of rod 16, whose lower end has a threaded portion 20, slideable in the tie 17 and screwed in a nut 21, having at its periphery a helical gearing in mesh with a worm 22, operated by a motor 23.

The above described parts are carried by carriage 35, bearing on tie 17 through the medium of springs 31, 32.

As in the preceding embodiment, the purpose of spring 31 is to cause rapid starting of the trolley and that of spring 32 is to cut off the electric current in the whole plant in case of overloading.

The operation is as follows: the bucket, after dumping, is returned towards the filling point, in the direction of arrow F¹ by the hoisting cable. Counterweight 7 rises between bars 13, 14 and along rod 16 towards the upper end of its stroke, until it engages abutment 15 or 19. At this moment, rod 16 exerts a pressure upon the springs. Spring 32 resists compression as the normal traction is insufficient to depress said spring. However, spring 31 is slightly compressed as the trolley stops. Upon unwinding rope 3, bucket 4 is moved down but its weight exerts a traction which overcomes the recall-effort of the counterweight, so that the trolley remains stationary. When the bucket engages the goods to be taken in, brake 11 maintains the bucket in place.

The operator then winds up cable 3, bucket 4 becomes filled and is then raised. At this time, the effort exerted on the hoisting rope 3 is considerably increased and is integrally transmitted to the spring 31, which is thereby compressed. When the bucket is gripped in its head 8, the operator slackens rope 3, whereby the counterweight becomes preponderant and, under the joint action of this counterweight and spring 31, the trolley starts rapidly in order to return to the dumping point.

If, by reason of the bucket being impeded in the course of its upward movement or otherwise, the hoisting effort becomes excessive, after spring 31 has been fully compressed, spring 32 collapses in turn, so that washer 33 operates switch 34, which automatically cuts off the electric current.

Should it be desired to reduce the run of the trolley in its return stroke toward the filling point, rod 16 will be so turned that the abutment 15 registers with the slot 18 of counterweight 7 whereas abutment 15a is placed crosswise thereto (Figs. 2 and 3), or abutment 19 will be raised or lowered by means of motor 23. The latter may be rotated continuously, at a constant or variable speed, in order to modify at every instant the position of the abutment.

In the example shown in Fig. 6, the abutment 36 cooperates directly with trolley 1, and springs 31, 32 are threaded on a rod 37, adapted to slide in a support 38 and to operate a switch 34. The 15 operation is identical to that of the preceding embodiments.

It is to be understood that the invention is not limited to the embodiments described and shown, which have been set forth merely by way 20 of example.

Having now described my invention, what I claim as new and desire to secure by Letters Patent is:

1. A hoisting device comprising a stationary 25 structure embodying a substantially horizontal runway, a trolley movable along said runway, a grab bucket carried by said trolley, a hoisting cable connected to said bucket, guiding means for the hoisting cable on said trolley whereby said 30 hoisting cable is adapted to draw the trolley from the dumping to the filling point, a recall cable attached to the trolley, a counterweight attached to said recall cable, means for guiding said recall cable on said stationary structure whereby the 35 recall cable is adapted to draw the trolley from the filling to the dumping point, an abutment carried by said stationary structure for stopping the movement of said trolley under the action of said recall cable, two springs of different yielding resistances operatively connected with said abutment, the lighter spring being adapted to start the reverse movement of the trolley and means for preventing any further action of the hoisting cable when the heavier spring is compressed.

45 2. A hoisting device as claimed in claim 1 wherein said abutment and springs are mounted on said runway and engage with the trolley.

PIERRE JEAN-MARIE
THÉODORE ALLARD.
